UNITED STATES PATENT OFFICE.

CARL D. BROWN, OF HOPEDALE, MASSACHUSETTS, ASSIGNOR TO DRAPEE CORPORATION, OF HOPEDALE, MASSACHUSETTS, A CORPORATION OF MAINE.

WARP STOP MECHANISM FOR LOOMS.

Application filed December 3, 1925. Serial No. 72,966.

To all whom it may concern:

Be it known that I, CARL D. BROWN, a citizen of the United States, and a resident of Hopedale, in the county of Worcester and State of Massachusetts, have invented an Improvement in Warp Stop Mechanisms for Looms, of which the following description, in connection with the accompanying drawings, is a specification, like characters on the drawings representing like parts.

This invention relates to warp stop mechanisms for looms whereby upon the occurrence of a fault in the warp threads the loom will be stopped.

It is now the common practice to provide looms with warp stop mechanisms which are usually, though not always, placed between the whip roll and shedding mechanism or heddle frames. Such warp stop mechanisms have been provided with warp supports and drop wires which are sustained by the intact warp threads during weaving, and on the occurrence of a warp fault, a detector mechanism has been influenced by the drop wire which fails to be supported by its warp thread, and through such detector mechanism the loom is stopped.

Where the warp stop mechanism is placed between the whip roll and shedding mechanism, the varying positions of the whip roll, sometimes high and sometimes low in different looms, or, indeed, in the same loom, disturbs the support of the warp threads by the warp supports, and perchance, also, may sustain the drop wires in improper relation to the cooperating parts.

In looms of this general type it is desirable that the plane of the warp threads as they pass over the warp supports of the warp stop mechanism, shall be coincident with the plane passing through the warp supports, and an object of the present invention, therefore, is to provide means whereby the warp stop mechanism as a whole, including the warp supports, may be angularly disposed in accordance with the height of the whip roll and the plane of the warp threads between the whip roll and shedding mechanism, so that the warp threads as they pass through the warp stop mechanism shall lie in the plane of the warp supports.

In accordance with the present invention in one aspect thereof, the warp stop mecha-

nism as a whole, including the warp supports, is mounted upon side frames, one at each side of the loom, each provided with a web having an arcuate guide, preferably formed on the arc of a circle, the center of which is in the plane passing through the warp supports, and such side frames are mounted upon side supports, one at each side of the loom, provided with complementary guides for directing the angular movement of the warp stop mechanism about the center of the arc, and securing means, such as bolts, are provided for securing the side frames and side supports in their co-related angular relation to bring the plane of the warp supports into the plane of the warp threads.

The present invention is herein shown and described in connection with a warp stop mechanism of the general type of that disclosed in the Davis and Johnson Patent, No. 1,538,625, May 19, 1925.

The invention and new combination of parts will best be made clear from the following description and the accompanying drawings of one good form thereof.

In the drawings:

Fig. 1 is a side view of a loom and warp stop mechanism provided with the present invention, some of the parts being shown in section and others broken away;

Fig. 2 is an enlarged front elevation at one side of the warp stop mechanism, some of the parts being shown in section; and

Fig. 3 is an enlarged side elevation showing more particularly the side frames of the warp stop mechanism and side supports in their co-related relation for angular adjustment of the warp stop mechanism.

The loom frame 1, partly shown in Fig. 1, may be of any usual type or construction and at the rear portion thereof has, as usual, bearings for the support of the warp beam 2 on which the warp threads *a* are wound. Rising from the loom frame are the brackets 3, shown in the present instance as one convenient form of means for supporting the whip roll. The whip roll 4 may be of any usual type or construction, but in the present instance it is shown as mounted upon the arms 5, one at each side of the loom, said arms being secured to the studs or shaft 6. From the whip roll 4 the warp threads *a* extend frontwardly of the

loom through the warp stop mechanism, to be hereinafter described, and forward of the warp stop mechanism the warp threads pass through the shedding mechanism, as usual, which in the present instance is graphically indicated as comprising the heddles 7 and 8. The means for forming the shed in the warp threads is not herein illustrated because it forms no essential part 10 of the present invention.

The side frames of the loom have mounted thereon the brackets 9, to the top portion 10 of which are secured the bearing arms 11, one at each side of the loom, and held to their respective brackets by means such as the bolts 12. Each of the bearing arms 11 has the elongated bearing 13 in which is adjustably mounted the post 14 which may be secured in vertically adjusted position by 20 means of the set screws 15.

Surmounting each of the posts 14 is a crown piece, constituting the side supports for the side frames of the warp stop mechanism, and each comprising a socket portion 25 16 secured to the posts by a set screw 17. Extending upwardly from the socket portion 16, the crown piece is provided with a flange or web 18, preferably curved as shown, the arcuate guide 19, Fig. 2, and the bolts 20, for 30 a purpose as will presently appear.

The warp stop mechanism as herein shown comprises the side frames 21, one at each side of the loom, and such side frames between them carry the warp stop mechanism. 35 Each side frame is provided with warp bar supporting sockets 22 on its inner face, in which rests the warp support 23 extending transversely of the loom between the side frames. At the front portion of the side frames is another warp support 24, shown 40 in this instance as a bar extending between the side frames, and on the two warp supports 23 and 24 the warp threads should rest during weaving, consequently the plane extending between the top of the warp supports 23 and 24 should be in the plane of the warp threads leading between the whip roll and the shedding mechanism.

Under certain conditions of weaving and 50 with certain kinds or characters of thread constituting the warp or in different looms, the whip roll occupies different positions. Sometimes it is higher, in the use of some warps, or in some looms, and at other 55 times it is lower; consequently this variation in the position of the whip roll will vary the plane of the warp threads leading between the whip roll and the shedding mechanism, and in the absence of means to 60 properly position the warp stop mechanism, and particularly the warp rests thereof, the warp threads will be bent over one or the other of the warp rests and consequently not 65 properly maintain the drop wires in their supported position by the warp threads.

Each of the side frames 21 is provided with a depending flange 25 which is provided with an arcuate guide 26, Figs. 2 and 3, formed on the arc of a circle corresponding to the arcuate guide 19 of the crown 70 piece, the arc of said guide being formed preferably about a center in a plane passing through the warp supports 23 and 24. In the present instance of the invention, the arcuate guide 19 is shown as a depression 75 in the flange 18 of the crown piece, which is engaged by the arcuate guide 26, shown as a projection on the flange or web of the side frames. Each of the side frames is provided with slots 27 through which pass the bolts 80 20 and by which the side frames and crown piece are secured in operative position. By manual manipulation of the bolts, that is, by loosening the nuts 28, the warp stop mechanism as a whole may be angularly adjusted 85 in conformity with the plane of the warp threads extending between the whip roll and shedding mechanism. This condition is indicated in Fig. 1 wherein the warp stop mechanism is shown as adjusted to conform 90 to the plane of the warp threads when the whip roll is higher than usual.

The warp stop mechanism, as indicated, is of the general type of that shown and described in the Davis and Johnson patent, 95 previously referred to herein, but in conformity with the present invention, the parts of the warp stop mechanism are all carried by the adjustable side frames 21. Mounted in the side frames for movement transversely 100 of the loom are the toothed detectors 29, Fig. 2, which pass through the usual slots formed in the drop wires 30, and connecting the movable toothed bar 29 with the actuators 31, of which there are four in the present 105 instance, are the links 32, the construction being such that should the actuators 31 be actuated or moved in a direction transversely of the loom, the connected toothed bar or detector will be likewise actuated. 110

Extending outwardly from one of the side frames 21 are the brackets or arms 33 in which is mounted the shaft 34 carrying the rocker 35 on which are mounted the actuators 31. Each actuator 31 has two fulcrums 115 36 by which it is supported upon the rocker 35, and a spring 37 normally holds the actuators 31 in operative engagement with the rockers, as indicated in Fig. 2, with permissive movement, nevertheless, about one 120 of its fulcrums 36.

Pivotedly mounted at 38, Fig. 2, is the finger 39 having a pin 40 which is engaged with the associated actuator 31, the construction being such that should the actuator 31 125 be arrested in its movement, it will turn about one or the other of the fulcrum points 36 and move the outer end of the finger 39 downwardly, in the present instance. The outer end of the finger 39 rests upon a finger 130

41 pivotally mounted at 42, as more fully described in the patent to Davis and Johnson, and the finger 41 bears upon the end of the flexible wire 43 within the sheath 44, the 5 construction being such that should any one of the actuators 31 be arrested in its movement, the associated stop finger 39 will act upon the finger 41 to move the flexible wire 43 in its sheath to effect loom stoppage, substantially as more fully described in the 10 Davis and Johnson patent.

It will be noted that the parts of the warp stop mechanism above described are all mounted upon the adjustable side frame 21 15 and consequently move with it when its angular relation is changed to bring the plane of the warp supports into the plane of the warp threads.

The rocker 35 is connected to an arm 45 20 carrying a link 46 having a pin and slot connection at 47 with the arm 45, and said link 46 is connected to a rod 48 leading to a cam actuated by a going part of the machine, as usual.

25 Should the relative positions of the whip roll and shedding mechanism be changed from a horizontal to an incline, either upwardly or downwardly, the side frames of the warp stop mechanism may be relatively 30 adjusted angularly with relation to their supports to bring the plane of the warp rests into the inclined plane assumed by the warp threads, so that the warp threads will always rest upon the warp supports, and 35 such angular adjustment of the warp stop mechanism combined with its vertical adjustment, as hereinbefore described, readily adapts the warp stop mechanism to all conditions, in conformity with the plane of the 40 warp threads, either upwardly or downwardly, or on an incline. Only two warp supports are herein shown and described as extending between the side frames of the warp stop mechanism, but it is to be understood 45 that any suitable number of warp supports may be employed to sustain the warp threads on their passage through the warp stop mechanism. When the plane of the warp threads is relatively high, the side 50 frames may be adjusted in a vertical direction to cause the warp threads to rest upon the warp supports, and if the plane of the warp threads is inclined either upwardly or downwardly due to the different positions 55 assumed by the whip roll and the shedding mechanism, the side frames of the warp stop mechanism may be angularly adjusted about a center in the plane of the warp rests to bring the warp rests into parallelism with 60 the plane of the warp threads.

What is claimed is:

1. In a warp stop mechanism for looms, 65 the combination of a whip roll and shedding mechanism, a side frame at each side of the loom between the whip roll and shedding

mechanism, warp supports extending between the side frames, a series of drop wires and a drop wire detector supported by the side frames, a stop finger and transmitter carried by a side frame, a support for each 70 of the side frames, said side frames and supports having interengaging arc guides, and means for securing the side frames in different angular adjustments to accord with the plane of the warp threads extending between the whip roll and shedding mechanism. 75

2. In a loom, the combination of a whip roll and shedding mechanism, a warp stop mechanism between them including side 80 frames, drop wires and a drop wire indicator, warp supports extending between the side frames, a web extending from each side frame, a support at each side of the loom, 85 said side frames and supports having registering arc-shape guides for directing angular movements of the side frames to place the warp supports in the plane of the warp threads between the whip roll and the shedding mechanism, and means for securing the 90 parts in related position.

3. In a loom, the combination of a whip roll and shedding mechanism, warp stop mechanism between them, side frames on 95 which the warp stop mechanism is supported, each of the side frames having a web provided with an arcuate guide, a support for the side frames at each side of the loom provided with a complementary arcuate guide 100 for directing the angular movements of the side frames, and means for securing the side frames and supports together in related angular position in accordance with the plane of the warp threads.

4. In a loom, the combination of the whip roll and shedding mechanism, warp stop mechanism and side frames therefor between the whip roll and shedding mechanism, each side frame having a depending web provided with an arcuate guide, a support for the side frames at each side of the loom having a complementary arcuate guide, curved slots in one of said arcuate guides, 110 and bolts for securing the side frames to their supports in angular relation in conformity with the plane of the warp threads between the whip roll and shedding mechanism.

5. In a loom, the combination of the whip roll and shedding mechanism, warp stop mechanism and side frames therefor between the whip roll and shedding mechanism, each side frame having a depending web provided with an arcuate guide, a support for the side frames at each side of the loom having a complementary arcuate guide, curved slots in 115 one of said arcuate guides, posts at each side of the loom sustaining the supports, and bolts for securing the side frames to their supports in angular relation in conformity 120 with the plane of the warp threads.

with the plane of the warp threads between the whip roll and shedding mechanism.

6. In a loom, the combination of the whip roll and shedding mechanism, warp stop mechanism and side frames therefor between the whip roll and shedding mechanism including warp supports, each of the side frames having a web provided with a guide formed on the arc of a circle whose center is 10 in the plane passing through the warp supports, a support at each side of the loom for the side frames and provided with a guide of similar curvature, and means for securing the side frames to the supports in angular 15 relation to place the plane of the warp supports in the plane of the warp threads between the whip roll and shedding mechanism.

7. In a loom, the combination of the whip 20 roll and shedding mechanism, warp stop mechanism and side frames therefor between the whip roll and shedding mechanism including warp supports, each of the side frames having a web provided with a guide 25 formed on the arc of a circle whose center is in the plane passing through the warp supports, a support at each side of the loom for the side frames and provided with a guide of similar curvature, vertically adjustable parts carrying said side frame supports, and means for securing the side frames 30 to the supports in angular relation to place the plane of the warp supports in the plane

of the warp threads between the whip roll and shedding mechanism.

8. In a warp stop mechanism for looms, the combination of side frames having depending webs provided with a curved guide and adapted to support the parts of the warp stop mechanism, an adjustable post at each side of the loom, a crown piece surmounting each post and provided with a curved guide for engagement with the curved guide of the side frames, one of said guides having curved slots and the other carrying bolts engaged with the slots for securing the side frames to the crown pieces in angular relation in conformity with the plane of the warp threads.

9. In a loom, the combination of the whip 50 roll and shedding mechanism, a warp stop mechanism therebetween including side frames, a drop wire detector carried by the side frames, an actuator for the detector mounted upon one of the side frames, a web 55 carried by each side frame and having an arcuate guide, a side support for each side frame having a complementary arcuate guide for directing the angular movements of the side frames to place the warp supports in 60 the plane of the warp threads, and means for securing the side frames in their angular related position.

In testimony whereof, I have signed my name to this specification.

CARL D. BROWN.
